(57) CLAIM

The ornamental design for an oval shaped pager/phone device, as shown and described.

DESCRIPTION

FIG. 1 is a front elevational view of an oval shaped pager/phone device showing my new design; the broken line showing of the hand is for illustrative purposes only and forms no part of the claimed design;

FIG. 2 is an enlarged top plan view thereof;

FIG. 3 is a left side elevational view thereof;

FIG. 4 is a front elevational view thereof;

FIG. 5 is a bottom plan view thereof;

FIG. 6 is a rear elevational view thereof; and,

FIG. 7 is a right side elevational view thereof.
